UNITED STATES PATENT OFFICE.

LINNAEUS E. BAKER, OF FORT WAYNE, INDIANA, ASSIGNEE TO WAYNE OIL TANK AND PUMP COMPANY, A CORPORATION OF INDIANA.

ACTUATING MECHANISM FOR DISPENSING APPARATUS.

1,247,487.

Specification of Letters Patent. Patented Nov. 20, 1917.

Application filed December 8, 1916. Serial No. 135,736.

To all whom it may concern:

Be it known that I, LINNAEUS E. BAKER, a citizen of the United States of America, and resident of Fort Wayne, in the county of Allen and State of Indiana, have invented certain new and useful Improvements in Actuating Mechanism for Dispensing Apparatus, of which the following is a specification.

10 This invention relates to improvements in actuating mechanism for dispensing apparatus of that class used for dispensing oil and similar products, such as that set forth in my previous application filed May 28, 1915, 15 Sr. No. 30,878, for dispensing pumps. The object of the improvement is to afford a construction composed of operating parts for actuating a reciprocating pump so that its discharge stroke, which requires a greater 20 application of applied energy than its return stroke, may be accomplished with approximately the same energy as that required in the completion of the cycle of movement of the pump. Generally, in reciprocating pumps of this class, as the piston is moved in one direction, liquid is expelled from the device and also liquid is drawn thereinto for subsequent discharge; and during the reciprocal stroke the plunger 25 is moved to the opposite end of the pump cylinder without the transient passage of liquid through the pump. The latter movement of the plunger requires comparatively less applied energy than its former movement which lifts the liquid in the pump and expels it therefrom. The intention is, in the present invention, to provide mechanism by means of which the opposite movements of the pump plunger may be effected 30 by the application of uniform energy. And another object is to afford a construction for reciprocating the pump in its opposite strokes at differing velocities while the driving energy is applied at a constant rate.

45 The objects of the invention are accomplished by the construction illustrated in the accompanying drawings in which:

Figure 1 is a side elevation of a pump showing the invention applied thereto, the 50 view being partially in central section;

Fig. 2 is a front exterior view of the same;

Fig. 3 is a detail sectional view showing the gearing and clutch mechanism for actuating the same;

55 Fig. 4 is a detail view in cross-section on

the line $z-z$ of Fig. 3, showing the driving clutch and actuating yoke therefor;

Fig. 5 is a detail view in section in a plane at right angles to that of Fig. 3 and including additional parts; 60

Fig. 6 is a detail view showing the clutch controlling levers in their relative positions during the return stroke of the pump;

Fig. 7 is a similar view upon a smaller scale of the same parts as they are positioned at the end of the return stroke; 65

Fig. 8 is a similar view of the same during the discharge stroke;

Fig. 9 is a detail view showing a cross-section of the rear part of the standard on the line $z-z$ of Fig. 5, there being a broken away portion to show parts in a lower plane; and, 70

Fig. 10 is an elevation of Fig. 9, there being also portions broken away and in section. 75

Similar characters of reference indicate corresponding parts throughout the several views and having reference now to the same:

The pump proper is supported by a pedestal (1) and is provided with a cylinder (2), plunger (3), rod (4), and rack-bar (5), the latter being fixed upon the rod so that the plunger will become actuated accordingly as the rack-bar is reciprocated. The mechanism for actuating the rack-bar is supported by a standard (6) that surmounts the head (7) of the pump proper. The standard receives support also from the discharge pipe (8) that leads from the head. 90 A secondary discharge pipe (9) also leads from the pump-head. 80

The actuating mechanism is comprised of a drive-shaft (10) having attached thereto a crank (11), the center portion (12) of the shaft (10) being substantially square, and upon said portion is slidably mounted a ratchet member (13) adapted to be rotated with the shaft as the latter is turned. The opposite ends of the ratchet member have 100 an annular series of teeth (14) and (15) respectively, and have also engaged relation with a yoke (16) that is rigidly mounted upon an oscillating shaft (17). The drive-shaft has loosely mounted thereupon pinions (18) and (19), the latter of which meshes constantly with the rack-bar (5). Each pinion has in rigid connections therewith a toothed hub (20) and (21) respectively, the teeth of which are adapted to be 110

engaged respectively by the teeth on the corresponding ends of the ratchet member accordingly as the latter is shifted from one position to the other.

5 A back-gearing is mounted in the standard and consists of a counter-shaft (22) arranged in parallel relation with the drive-shaft and having fixed thereon a pinion (23) and gear (24), the former being in 10 mesh with the rack-bar and the latter meshing with the pinion (18) on the drive-shaft, so that as the drive-shaft is revolved and the ratchet-member is in engaging relation with the hub of the pinion (18) the rack-bar will become actuated through the medium of the gear (24), counter-shaft (22) and pinion (23), during which operation the pinion (19) idles upon the drive-shaft as it is rotated by the movement of the rack-bar. When the ratchet-member is shifted 15 so as to engage the hub of the pinion (19), and the drive-shaft is turned in the same direction as in the former instance, the rack-bar will be driven through the medium of 20 the pinion (19) in the opposite direction, during which operation the counter-shaft together with its fixed pinion and gear as well as the loose pinion (18) on the drive-shaft will rotate idly. The ratios between 25 the several pinions and gear are such that the driven actions of the rack-bar in its opposite strokes differ in velocity.

The pinion (25) on the counter-shaft is for actuating a counter which forms connections therewith through the slot (26) in the standard, the counter being no part of the invention, is not shown. Also, the shaft (22) projects through one side of the standard for the purpose of connection with an 30 indicator which also is not shown.

The primary oscillating member comprised of the shaft (17), yoke (16), and a lever (28), is provided for shifting the ratchet-member, and the secondary oscillating member comprised of the shaft (27), casting (31), and crank (38) having a roller (39), is provided for automatically actuating the primary oscillating member.

The oscillating shaft (17) extends in a 35 line at right angles to the drive-shaft, and the secondary oscillating shaft (27) extends in a line parallel with the former oscillating shaft. Upon the outer end of the shaft (17) is rigidly fixed the lever (28) having an upwardly extending lug (29) in which 40 is mounted an adjusting screw (30), and upon the outer end of the shaft (27) is rigidly fixed the casting (31) having oppositely extending ears (32) and (33) respectively and also a pendant lug (34), the latter being adapted to bear against the end 45 of the adjusting screw (30) which is carried by the lug (29) on the lever. A retracting spring (35) is connected at its ends 50 to studs (36) and (37) that project respec-

tively from the lever and ear (33) on the casting (31), and tends to hold the lever and casting so the lug of the latter will bear against the set-screw (30). The secondary oscillating shaft (27) has also fixed thereon 55 a crank (38) having a roller (39) mounted thereon that bears upon the edge of the adjacent flange (40) on the rack-bar. A retracting spring (41) is secured at its opposite ends respectively to studs (42) and (43), the former extending from the standard and the latter from the ear (32) of the casting (31), the spring having the tendency of holding the casting normally so that the roller (39) will bear against the flange (40). In the flange is made a recess (44) into which the roller may drop at the point where the rack-bar reaches the lowermost stage of its movement, the recess being located in the guide accordingly.

An adjustable stop (45) is mounted in the standard and is adapted to limit the upward movement of the rack-bar by contacting with a projection (46) at the lower end of the latter, and a plate (47) secured upon the pump-rod (4) at the upper end of the rack-bar serves to limit the downward movement thereof by contacting with the top of the standard through which it extends.

The apparatus has also a series of adjustable stops (48), (49) and (50) each of which is mounted upon a vertical oscillating rod (51) the ends of which are journaled respectively in the pump-head and standard. The said stops are spaced apart at suitable intervals and extend in different radii from each other so that any one or the other of the stops may be brought into the path of the projection (46) on the rack-bar accordingly as the rod (51) is turned, and thus arrest the upward movement of the rack-bar when the projection contacts with the stop. As a means for turning the rod (51) and holding the same in any of its adjusted positions, and as a means for indicating the 100 position of its adjustment, a casting (52) is secured fixedly to the rod at its upper end adjacent the projecting portion of the standard and is provided with a segmental flange (53), the upper face of which bears designating characters (54) which are significant of the various quantities of liquid discharged by the pump accordingly as the stops are positioned by turning the rod (51). The casting (52) has also a thumb-piece (55) for 105 manipulating the same, and also a notched flange (56), the notches of which are adapted to be engaged by a spring pressed ball (57) located in a perforated lug (58) that depends from the standard. When the ball 110 enters any of the notches of the flange, it tends to hold the casting from turning and the notches are so spaced apart that the detained positions will correspond respectively 115 with the corresponding operating positions 120 125 130

of the stops on the rod. The designating characters (54) are also spaced apart to correspond with the several positions of the stops, and an index (59) is secured to the 5 standard and overhangs the segmental flange at a convenient point so as to register properly with the designating characters as the latter are moved successively from one adjusted position to another.

10 One function of the lever (28) is to manually shift the clutch-member from one engaging position to the other as occasion may arise, and this is done by swinging the lever accordingly in opposite directions which 15 causes the oscillating shaft (17) to move with the result that the yoke fixed thereon shifts the clutch-member. This lever may be shaped so as to normally extend toward the right hand instead of toward the left 20 as shown, if so desired. However, such alteration would in no way change its function but may in some cases be more convenient for the operator.

When the rack-bar is at its lowermost position and the roller (39) on its crank rests in the recess (44), and is held therein owing to the action of the spring (41), the lug (34) bearing against the set-screw (30) holds the lever in position for the engagement of 25 the ratchet-member with the hub (20) on the pinion (18), as illustrated in Figs. 3 and 7. Upon the rotation of the crank right handedly, when the parts are thus positioned, the ratchet-member engages with the pinion 30 (18) and thereupon motion will be transmitted through the gear, counter-shaft and pinion (23) to the rack-bar and cause the same to move upwardly. As the rack-bar rises, the roller is forced outward from the recess 35 and bears against the edge of the guide on the rack-bar, and owing to the consequent oscillation of the shaft (27), the lug (34) moves from the set-screw (30). The spring (35) tends to draw the lever so as to shift the 40 ratchet-member from its engagement, but the disengagement is resisted owing to the torque maintained between the drive-shaft and ratchet-member and also between the latter and the pinion during the application of 45 pressure to the crank. The teeth of the ratchet-member and adjacent hubs of the corresponding pinions may also be slightly undercut and thus afford greater resistance. Consequently driving relation between the 50 ratchet-member and pinion is maintained contrary to the action of the spring (35). At this stage the parts are positioned as 55 illustrated in Fig. 8. By continuing the movement of the crank the rack-bar is thus raised until interrupted by the stop, at which stage the pressure applied to the crank is relaxed by the operator, whereupon the ratchet-member becomes released from its 60 detained connection with the pinion (18) 65 and because of the action of the spring (35)

and lever (28), the ratchet-member is shifted into engagement with the pinion (19), the parts then being positioned as illustrated in Fig. 6. Upon the continuation of the right-handed movement of the crank 70 the ratchet-member actuates the pinion (19) accordingly and the rack-bar is consequently driven downwardly to its former position, the recess in the rack being then positioned to receive the roller, and thus admit movement of the secondary oscillating member. As pressure on the crank is relaxed by the operator at this stage, the oscillating members are returned to their opposite positions by the contraction of the spring (41), the 75 secondary member being actuated directly by the spring and the primary member being moved by the former member. The ratchet-member being shifted by the action of the primary member becomes reengaged with 80 the pinion (18). By manipulating the lever (28) at any stage in the movement of the rack-bar, the ratchet-member may be shifted from connection with one of the pinions into 85 engagement with the other, the yielding of 90 the spring (35) admitting of the necessary action of the lever. Thus, the direction of movement of the rack-bar may be reversed at will as the crank is rotated by merely shifting the lever from one of its positions to 95 the other. Also, at any stage during the upward movement of the rack-bar, the applied pressure to the crank may be relaxed so as to release the ratchet-member from connection 100 with the pinion (18) whereupon the ratchet-member will become shifted into engagement with the pinion (19) owing to the action of the spring (35), and by continuing the motion of the crank the movement 105 of the rack-bar becomes reversed and returned to its lowermost position with the result that the ratchet-member reengages the pinion (18) upon relaxation of the pressure applied to the crank.

What I claim is:—

1. In apparatus of the class described, a pump proper including a rack-bar fixed on the pump-rod; a standard; a counter-shaft having a pinion and gear fixed thereon, the pinion meshing with the rack-bar; a drive 115 shaft having a crank for actuating the same and having two pinions loosely mounted thereon, one of which meshes with the rack-bar and the other with the gear, each pinion having a toothed hub; a ratchet-member on 120 the drive-shaft, adapted to be driven thereby and to be shifted thereon longitudinally into driving relation with either pinion adjacent thereto; an oscillating shaft having means in connection therewith for shifting the ratchet-member, a secondary oscillating shaft having in connection therewith a following member comprised of a crank and roller adapted to bear against the side of the rack-bar, the latter having a recess therein 125 130

- adapted to receive the roller when the rack-bar is at one end of its stroke; a spring actuated member fixed upon the secondary oscillating shaft; a hand lever fixed upon the former oscillating shaft and having adjustable means for contacting with said member; and a spring in connection with said member and lever tending to maintain contact therebetween.
2. In apparatus of the class described, a pump proper including a rack for actuating the same; a drive-shaft having means in connection therewith for its manipulation; two pinions loosely mounted on the drive-shaft, one of which meshes with the rack, and moves it in one direction; a counter gearing engaging the other pinion and rack and being adapted to move the latter in the opposite direction; a ratchet-member longitudinally movable on the drive-shaft and being adapted to be shifted into engagement with either pinion and drive the same when the drive-shaft is turned in one direction; and a mechanism having connection with the ratchet-member and bearing relation with the rack, the bearing surface of the latter being so shaped as to cause said mechanism to shift said member at one end of the stroke of the rack.
3. In mechanism of the class described, a pump proper including a rack; a mechanism including a drive-shaft and reversible gearing for reciprocating the rack; an oscillating member having means in connection therewith for reversing said gearing; a secondary oscillating member including a follower that has bearing relation with the rack; a spring in connection with the secondary oscillating member for holding the follower in contact with the rack; and another spring connecting said oscillating members tending to actuate the former oscillating member when the secondary oscillating member is actuated, the bearing surface of said rack being so shaped as to actuate the latter member through the medium of the follower at one end of the stroke of the rack.
4. In apparatus of the class described, a pump proper including a rack, the latter having a flange with a recess therein; a back gearing having driving relation with the rack; a drive-shaft; two pinions loosely mounted on the drive-shaft; one meshing with the rack and the other with the back-gearing; a ratchet-member slidably mounted upon and rotatable with the drive-shaft; a primary oscillating member for shifting the ratchet-member; a secondary oscillating member having bearing relation with the rack and being adapted to be actuated thereby at one end of the stroke thereof, and being also adapted to actuate the primary oscillating member; a spring coupling said oscillating members; and another spring for holding the secondary oscillating member in contact with the rack.
5. In apparatus of the class described, a pump proper including reversible gearing for actuating the same; a primary oscillating member for controlling said mechanism; a secondary oscillating member controlled by the pump actuating mechanism; and a spring connection between the primary and secondary oscillating members for actuating the former in one direction, the secondary oscillating member being adapted to actuate the primary member independently of said spring connection.
6. In apparatus of the class described, a pump proper including a reversible driving gear for actuating the same; a primary oscillating member for reversing said mechanism; and a secondary oscillating member controlled by the pump mechanism for actuating the primary oscillating member.
7. In apparatus of the class described, a pump proper including a reversible driving gear for actuating the same; a primary oscillating member for driving said mechanism reversibly accordingly as actuated; a secondary oscillating member controlled by the pump mechanism for shifting the primary oscillating member; and springs in connection with the primary and secondary members for holding same in actuating relation with each other and with the pump mechanism.
8. In apparatus of the class described, a pump proper including a rack and reversible driving gear for actuating the same, the said rack having a flange with a recess therein; a primary oscillating member having means in connection therewith for actuating the rack directly and also indirectly through said reversible gear accordingly as shifted; and a secondary oscillating member controlled by the pump mechanism and governing the primary member.
9. In apparatus of the class described, a pump proper including a rack and gearing for actuating the same, the said rack having a flange with a recess therein; a primary oscillating member having means in connection therewith for reversing said gearing or actuating the rack directly accordingly as shifted; a secondary oscillating member having bearing on the flange of the rack and adapted to engage in said recess therein; and a spring connecting the primary and secondary members, the latter member being adapted to engage and actuate the former member directly and also actuate the former member through the medium of said spring in the opposite direction.
10. In apparatus of the class described, a pump proper including a rack and gearing, and also mechanism for actuating the rack directly in one direction and indirectly in the opposite direction through the medium

of the gearing; a primary oscillating member having means in connection with the mechanism for effecting the driving relation thereof with the rack for said gearing accordingly as shifted; a secondary oscillating member adapted to shift the primary member by direct contact therewith, and having also bearing relation with the rack, said rack being shaped to actuate the secondary member at one end of its stroke; a spring holding the secondary member in contact with the rack; and a spring connect-
ing the primary and secondary members adapted to actuate the primary member and release the same from engagement with said mechanism when driving force upon the latter is relaxed.

In testimony whereof I affix my signature in presence of two witnesses.
